CLAIM

The ornamental design for an electric bike frame as shown and described.

DESCRIPTION

FIG. 1 is a top, rear and left side perspective view of an electric bike frame showing my new design; FIG. 2 is a bottom, front and right side perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof; and,

FIG. 8 is a bottom plan view thereof.

The broken lines in the figures are for the purposes of illustrating portions of the electric bike frame, which form no part of the claimed design.

1 Claim, 8 Drawing Sheets(56)
